UNITED STATES PATENT OFFICE.

JOHN MILLER FLEMING, OF EDMONTON, ALBERTA, CANADA.

DASH-CHURN.

1,265,187.

Specification of Letters Patent.

Patented May 7, 1918.

Application filed July 2, 1917. Serial No. 178,223.

To all whom it may concern:

Be it known that I, JOHN MILLER FLEMING, of the city of Edmonton, in the Province of Alberta, Dominion of Canada, have invented certain new and useful Improvements in Dash-Churns, of which the following is the specification.

This invention relates to improvements in dash churns and the object of the invention is to provide means for drawing air down into the body of the cream so that it will pass up through the cream and thereby drive all impurities from the cream and produce a better grade of butter and at the same time provide a machine which will economize both time and labor and which may be readily adjusted for the different sizes of vessels and different depths of cream. It consists essentially of the following arrangement of parts as hereinafter more particularly explained by the following specification.

Figure 1 is a side elevation of my churn showing the cream containing vessel, dasher and major portion of the supporting structure for the operating mechanism in section.

Fig. 2 is an enlarged sectional view of the dasher.

Fig. 3 is a plan section on line $x-y$ Fig. 2. 30 Fig. 4 is a plan section on line $x'-y'$ Fig. 1.

In the drawings like characters of reference indicate corresponding parts in each figure.

1 indicates the main base or foot of the machine provided with a central tubular portion 2 split vertically at 3 and provided with lugs 4 and 5 through which a bolt 6 extends to draw the split ends of the sleeve together. 7 is the main standard or column. 8 is a table secured to the upper end of the column 7 and provided with a recessed portion 8* as indicated in the dotted lines in Fig. 1, into which a vessel 9 for containing cream fits at its base. 10 is a supplemental hollow standard extending upwardly from the table 8 and suitably secured thereto. The standard 10 is also provided with a split upper end 11 provided with lugs 12 and bolt 13 extending through the lugs to draw them together. 15 is the main casting for supporting the operating mechanism of the machine. 16 is a side shaft extending from the casting 15 and on which is mounted a gear wheel 17 provided with a crank handle 18 in proximity

to its periphery. 19 and 20 are horizontal bearings formed at the upper end of the casting 15 and in alinement one with the other. 21 is a shaft journaled in the bearings 19 and 20 and provided at one end with a gear pinion 22 meshing with the gear wheel 17. 23 is a crank wheel secured to the opposite end of the shaft 21. 24 is an arm extending from the casting 15 and provided at its outer end with a vertical bearing 25. 26 is a vertically movable rod slidably held within the bearing 25 and provided with jaws 26* at its upper end. 27 is a link pivoted by a bolt 27* between the jaws 26* and pivotally connected at its upper end by a bolt 28 to the crank wheel 23 in proximity to its periphery. 29 is a bracket secured to the rod 26 by a set screw 30 or any other suitable device. 31 is the main rod of the dasher clamped at its upper end within the bracket 29 by a set screw 32. 33 is a cylindrical member surrounding the rod 31, the rod being secured centrally within the cylindrical member by spiders 34 and 35 so as to form an annular space between the inner face of the cylinder 33 and the rod 31. 36 is the head of the dasher comprising radially extending arms 37 and an annular rim 38 formed integral with the arms; the lower end of the tubular member 33 is provided with an annular flange 39 and 40 are screws extending through the flange 39 into the head 36 whereby the head 36 is secured to the cylindrical member 33. 41 is a spider the upper periphery portion of which fits in an annular recess 42 formed in the head of the dasher 36. 43 is a rod slidable within the spider 41. 44 is a split pin extending diametrically from the upper end of the rod 43. 45 is a spiral compression spring extending between the split pin 44 and the spider 41. 46 is a metal disk forming the valve head fitting against the lower face of the dasher head 36 so as to normally close the orifice 36* formed in the center of the dasher. The disk 46 is provided with a central orifice 36* from which the lower threaded end of the rod 43 extends. 47 and 48 are nuts whereby the disk 46 is secured in position upon the rod 43.

Having described the principal parts involved in my invention I will briefly describe the operation of the same.

The handle 18 is grasped by the operator and the wheel 17 rotated thereby driving the pinion 22, shaft 21, crank wheel 23 and

imparting thereby a reciprocating vertical movement with the rod 26 by means of the connecting link 27 extending between the rod 26 and the crank wheel 23. By this 5 operation the dasher of the churn is reciprocated vertically in the body of cream contained within the receptacle 9. During the upward movement of the dasher the displacement of the cream creates a vacuum 10 which draws open the valve formed by the disk 46 allowing air to rush through the tube 33 into such space formed by the displacement of the cream. During the downward movement of the dasher upward pressure 15 of the cream forces the disk 46 upward against the head 36 closing the orifice 36* and thereby preventing the cream rising up into the cylindrical member 33. The air which has thereby been drawn into the body 20 of cream rises up through such body and any impurities in the cream are united therewith and carried up thereby into the atmosphere, thereby clearing the cream of all such impurities. If it is desired to ad- 25 just the apparatus in accordance with the size of the receptacle used or the depth of the cream within the receptacle, all that is necessary to do is to loosen the bolt 6 and raise the column 7 to the required height, 30 the main casting 15 supporting the driving gear may also be adjusted by loosening the bolt 13 and raising the casting 15 upward to the required height and retightening the bolt 13.

Copies of this patent may be obtained for five cents each, by addressing the "Commissioner of Patents, Washington, D. C."

From this description it will be seen that I have devised a very simple form of dasher 35 churn which may be operated manually with a minimum amount of power which may be operated more rapidly and thereby more rapidly convert the cream into butter 40 and at the same time provide means for permeating the body of the cream with fresh air which, rising through the cream, draws all impurities contained in the cream to it so that they are finally carried off as such 45 air rises to the surface of the cream.

What I claim as my invention is:

In a device of the class described, a dasher comprising a central rod, a head having a central opening, a tubular member remov- 50 ably secured to the head and extending upwardly from the head around such opening and into the center of which the lower portion of the dasher rod extends, spider mem- 55 bers for connecting the dasher rod to the cylindrical member, a disk valve bearing against the lower face of the head, a spider member supported within the cylindrical member in proximity to the head, a stem extending freely from the spider member 60 to the lower end of which the valve disk is secured, a bearing piece carried by the upper end of the stem, and a compression spring extending between such bearing piece and the spider. 65

In witness whereof I have hereunto set my hand.

JOHN MILLER FLEMING.
